(57) **CLAIM**

The ornamental design for a remote control ball ejector, as shown and described.

DESCRIPTION

FIG. 1 is a side elevational view of the remote control ball ejector with the understanding that the opposite side elevational view is the same;

FIG. 2 is a side elevational view rotated approximately forty five degrees from the view of FIG. 1;

FIG. 3 is a side elevational view rotated approximately ninety degree from the view of FIG. 2;

FIG. 4 is a top plan view; and,

FIG. 5 is a bottom plan view.
